UNITED STATES PATENT OFFICE.

HARRY V. HAIGHT, OF SHERBROOKE, QUEBEC, CANADA, ASSIGNOR TO INGERSOLL-RAND COMPANY, OF JERSEY CITY, NEW JERSEY, A CORPORATION OF NEW JERSEY.

UNLOADING SYSTEM.

Application filed June 26, 1925. Serial No. 39,668.

This invention relates to unloading systems and presents features of general application especially advantageous when applied to a system in which it is desired to maintain the power consumption within a predetermined maximum limit. In such a system there may be two or more devices consuming power, one of which is adapted to be unloaded to reduce the power consumption while the other is operating or at least during its accelerating period so that the total power consumed shall not exceed a given amount.

An instance of a system to which this invention is applicable is found in most mine installations in which there is provided a main air compressor for furnishing air for operating miscellaneous machines, such as drills, and a hoist for raising and lowering material from the mine shaft. Generally, the hoist and compressor are both electrically driven and the power is purchased at a rate based upon the maximum demand. It is therefore desirable that peak-loads be avoided. At the starting up of the hoist and during its accelerating period, a heavy draft of current occurs for a short time so that it is desirable that the current consumption of other apparatuses such as the compressor be dismissed at that time.

One object of this invention is to enable the peak-load due to sudden power demands of short duration to be done away with. This is accomplished by providing apparatus which unloads the compressor or one of the power consuming devices, while another, such as a hoist, is drawing an abnormally large amount of current, as for instance, during its accelerating period. Another object of the invention is to control the various power consuming devices pneumatically such as by means of compressed air, this being available in installations including a compressor. It will be understood that this system may be employed in steam driven plants. One advantage of this hoist is that it will not be necessary to provide a power generating plant of a size sufficient to supply steam for peak-loads in such a case.

Other objects and advantages of the invention will be in part obvious and in part pointed out hereinafter.

In the drawing forming part of the specification and in which similar reference characters refer to similar parts,

Figure 1 is a diagrammatic representation of a system including an air compressor and a hoist provided with power unloading means for the compressor automatically operable when the hoist is being started and during its acceleration period, 60

Figure 2 represents a power consumption curve for the air compressor motor,

Figure 3 represents a power consumption curve of the hoist motor during its acceleration period, 65

Figure 4 represents the combined power consumption curves of the air compressor motor and the hoist motor during the accelerating period of the latter, 70

Figure 5 is a detail view partly in section of an electrically controlled pilot and relay valve for unloading the air compressor,

Figure 6 is a detail of the pneumatic relay for operating the unloading mechanism 75 of the air compressor,

Figure 7 is a view of a pneumatic relay mechanically operated, and

Figure 8 is a detail view of the mechanically operated pneumatic relay shown in 80 Figure 7 in another of its operating positions.

Referring to the drawings and more especially to Figure 1, the compressor includes a pair of cylinders A and B operated by a single electric motor C associated with the electric power lines D by means of a suitable knife switch E. The air from the cylinders A and B is discharged through a conduit F to a receiver G from which the compressed air is discharged into pipe lines (not shown) leading to the work. The compressor cylinders A and B are adapted to be unloaded when the pressure in the receiver G reaches a predetermined maximum and to this end there is provided a regulator having a cylinder H and piston (not shown) therewithin exposed to air supplied from the receiver G through a pipe J. The regulator is substantially like that disclosed in Patent No. 100 1,099,457 of June 9, 1914, granted to F. V. D. Longacre and is provided with a pilot valve chest K having a plurality of air lines L, O, P and Q into which a regulator valve (not shown) within the valve chest K is arranged to control the flow of compressed air or other suitable motive fluid for selectively operating unloading valves R, S, T and U for the cylinder B and unloading valves V, W, X and Y for the compressor cylinder A 105 110

substantially as shown in Prellwitz Patent No. 1,027,757 of May 28, 1912. The regulator valve within the valve chest K is arranged to successively supply compressed air to the pipes L, O, P and Q for successively operating pairs of unloading valves. For instance, at the first stage of unloading the pilot valve releases compressed air in the pipe L which leads to the unloading valves R and X whereupon suitable clearance chambers (not shown) in the cylinders B and A respectively are opened at opposite ends of the cylinders B and A respectively, causing one quarter unloading of the compressor. Preferably the unloading of the cylinders A and B is equal and opposite in the cylinders A and B so as to balance the load on the motor C. The pipes L, O, P and Q may be successively connected so as to operate successive unloading valves of the compressors A and B. When all of the unloading valves R, S, T, U, V, W, X and Y are operated the compressor is completely unloaded and the power consumed by the motor C is a minimum.

In combination with the compressor above described this invention contemplates the use of a second power driven device operated from the electric power lines D which may be a hoist motor b arranged to operate a hoist drum d through gearing of any suitable description. The hoist motor b is adapted to be controlled by a starting rheostat e which may be hand controlled.

The starting rheostat is provided with a rotating shaft f which, as shown in Figure 5, also supports a cam g to be rotated with the shaft f. As the shaft f is rotated in a clockwise direction to operate the rheostat e for starting the motor b the cam g is adapted to strike against a block h pivoted on a lever k cooperating with an arm j on the switch blade p causing the switch blade p to break contact with a switch contact q.

The lever k is pivoted at one end on a pin r mounted on a base s and is provided with a spring t supported on a boss u on the base s tending to press the lever k toward the left normally out of engagement of the arm j on the switch blade p. The block h is pivoted on a pin v and bears against a pin w mounted on the lever k forwardly and below the block h so as to prevent downward movement of the block h when pressed by the cam g from above. A spring x normally tends to hold the block h against the pin w. Due to the pivoted arrangement of the block h on the lever k the cam g upon rotating in a counter clockwise direction will strike the block h moving it upwardly without operating the lever k.

The switch blade p and the switch contact q are adapted normally to complete a circuit through the conductor y leading from one of the electric conductors D to a binding

post z, a spring 2, the switch blade p, a switch contact q, a binding post 3, a conductor 4, an electromagnet 5 and a conductor 6 to the other side of the line D.

The electromagnet 5 forms part of an electropneumatic relay having an armature 7 pivoted intermediate its ends on a pin 8 and connected at its lower end by a link 9 to a lever 10 having a pivot 10'. The base 11 of the electropneumatic relay supports a valve 75 chamber 12 having a bore 13 within which a valve stem 14 is adapted to reciprocate. The end of the valve stem 14 extends from the valve chamber 12 into the path of the lever 10 so that when the armature 7 is released 80 upon deenergization of the electromagnet 5 a spring 15 attached to the lower end of the armature 7 is adapted to retract the lower end of the armature causing the lever 10 to press against the end of the valve stem 14 pressing it inwardly. A valve 16 is mounted on the valve stem 14 being separated therefrom by a reduced neck 17 permitting the passage of air into the bore 13 of the valve chamber and thence into a transversely 90 bored passage 18 arranged to be connected by means of a pipe connection 19 with a pipe 20. The valve 16 is provided with a tapered seat 21 and is arranged to open and close communication between a larger bore 22 in the valve chamber 12 and the passage 18 leading from the bore 13. The larger bore 22 is provided with a screw threaded plug 23 having a passage 24 leading to a pipe threaded aperture 25 for connection with an air 100 supply pipe 26. As shown in Figure 1 the pipe 26 is supplied with compressed air by a supply pipe 27 connected with the receiver G.

Upon energization of the electromagnet 103 5 the armature 6 draws the lever 10 out of the path of the valve stem 14 upon the air pressure supplied to the interior of the valve chamber 12 seats the valve 16 shutting off the supply of compressed air to the pipe 110 20. Upon deenergization of the electromagnet 5 the armature 7 drops back by tension of the spring 15 and the lever 10 presses against the valve stem 14 unseating the valve 16 and permitting compressed air to 115 flow from the interior of the valve chamber 12 past the valve 16 into the pipe 20.

The pipe 20 connects with a pilot valve shown in detail in Figure 6. The pilot valve 120 comprises a body portion 28 having a cylindrical bore 29 to fit closely a plunger 30 upon which is mounted a flat valve 31 secured to a bolt like extension 32 of the plunger 30 by means of a nut 33 and washer 34. The pipe 20 is attached to the body portion 28 of the pilot valve at a threaded aperture 35 leading to a recess 36 above the plunger 30. A threaded plug 37 closes the upper end of the body portion 28 and is removable to permit the plunger 30 to be 130

withdrawn from the body portion 28. Compressed air is supplied to the pipe 20 from the electromagnetic relay into the recess 36 and air pressure forces the plunger 30 down causing the flat valve 31 to seat on a valve seat 38 closing communication from a chamber 39 within the body portion 28 to a small longitudinal bore 40. Upon closure of the valve 16 of the electropneumatic relay the air contained in the pipe 20 and the recess 36 is permitted to leak out through a bleeder hole 41 in the body portion 28.

Upon depression of the plunger 30 the bolt like extension 32 is arranged to engage the end 42 of a second plunger 43 in alignment with the plunger 30 provided with a valve 44 attached to the plunger 43 by means of a nut 45 and washer 46. The plunger 43 is arranged to reciprocate in a bore or guide 47 in a plug 48 closing the lower end of the body portion 28. The valve 44 is adapted to close communication between a lower chamber 49 in the body portion 28 and the longitudinal bore 40. The chamber 49 is constantly supplied with compressed air from the pipe 27 through a pipe 50 connected with the chamber 49 at the threaded aperture 51. The upper chamber 39 is provided with an atmospheric escape port 52 which permits compressed air to exhaust from the longitudinal bore 40. The valve 44 is prevented from opening and closing too suddenly by a dash pot formed by the bore 47 and the plunger 43 there being a bleeder port 53 leading from the lower chamber 49 to the bore 47 below the plunger 43.

One of the functions of the pilot valve is to supply and exhaust compressed air to and from a cylinder 54 (Figure 1) provided with a piston 55 connected by means of a connecting rod 56 with the arm 57 of the regulator. To this end there is provided a pipe line 58 connected at the pipe threaded aperture 59 with a passage 60 leading to the longitudinal bore 40 of the body portion 28 of the pilot valve. Compressed air admitted into the cylinder 54 causes the piston 55 to rise lifting the arm 57 and operating the pilot valve within the valve chest K to unload the compressors A and B in the manner above described.

Upon operation of the rheostat e to trip the switch blade p the electromagnet 5, being deenergized, permits the valve 16 to open, supplying compressed air to the recess 36 of the pilot valve, depressing the plunger 30 as shown in Figure 5, causing the valve 31 to close communication to atmosphere through the port 52 from the pipe line 58, and unseating the valve 44 to permit compressed air to flow from the pipe 50 through the longitudinal bore 40 and the pipe line 58 to the cylinder 54. Thereupon the regulator arm 57 rises, causing the regulator valve within the valve chest K to oper-

ate the unloader valves R, S, T, U, V, W, X and Y, unloading the compressor and thereby diminishing the current consumed by the compressor motor C. The unloading of the compressor motor C is simultaneous with the maximum consumption of power by the hoist motor b since, as is well known, an electric motor upon starting under load draws a much greater current than at greater speeds.

Upon rotation of the shaft f beyond the starting position of the rheostat e the cam g disengages the block h on the lever k permitting the switch blade p again to contact with the switch contact q deenergizing the electromagnet 5 and closing the valve 16, whereby supply of compressed air to the recess 36 is cut off. The compressed air remaining in the recess 36 is permitted to escape through the bleeder 41 to atmosphere. The pressure on both sides of the plunger 30 under this condition is atmospheric and pressure within the longitudinal bore 40 against the valve 31 unseats the latter valve causing a sudden pressure drop in the longitudinal bore 40 and on the valve 44. The air in the lower chamber 49 being at full line pressure causes the valve 44 to seat and shut off the supply of compressed air to the longitudinal bore 40; the remaining compressed air in the cylinder 54 associated with the regulator arm 57 and the compressed air in the pipe line 58 leak back through the passage 60 and the bore 40 past the valve 31 to atmosphere through the port 52. This permits the regulator arm 57 to lower by gravity and correspondingly the regulator valve within the valve chest K reloads the compressor cylinders A and B.

Figure 2 represents approximately the power consumption curve of the compressor motor C starting at a time represented by the point 61 with compressor cylinders A and B unloaded and continuing so to a time represented at the point 62 at which the re-loading of the compressor starts. 63 represents the time of complete loading, from which the curve continues as a straight line, the current consumption being substantially constant at full compressor loading.

Figure 3 represents a typical power curve of a motor such as the hoist motor b. The power increases from zero to a maximum as represented at the portion 64 of the curve as soon as the rheostat is operated. The rate of current consumption drops off slightly, as is indicated in the sloping portion 65, as the motor accelerates and then drops down suddenly as indicated in the steeper sloped portion 66 thereafter dropping off more gradually, as represented by the gently sloping portion 67, as the motor speeds up.

The combined power consumption of the two power consuming devices, the compressor motor C and the hoist motor b is represented

in Figure 4 the curve shown in Figure 3 being superposed on the curve shown in Figure 2. The dotted portion 68 represents the peak eliminated by unloading the compressor motor C and the peak now is represented by the ordinate at the point 69. The charge for power consumed by the combined plant is based upon the peak-load represented at 69 rather than the greater peak-load represented at 68.

In Figures 7 and 8 there is shown a modified form of pilot valve adapted to be actuated mechanically instead of through the medium of the electropneumatic relay shown in Figure 5. This pilot relay is shown arranged to be actuated in combination with a rheostat in which the moving element instead of being a revolving shaft as shown at f in Figure 5 is a reciprocating member 70 provided with a cam surface 71 for actuating a lever 72 pivoted at a pin 73 on a base 74. The lever 72 is provided with a pivoted block 75 similar in function to the block h pivoted on a pin 76 mounted on the lever 72 and spring pressed against a pin 77 on the lever 72 by means of the spring 78. The spring 78 and the block 75 are held on the pin 76 by means of a washer 79 held in place by a cotter pin 80. The body portion 81 of the pilot valve is provided with a flat valve 82 faced with suitable seat material 83 cooperating with the valve seat 84 between a chamber 85 connected by means of the pipe 50 with a constant source of compressed air 55 and a smaller bore 86 leading to a central chamber 87. The valve stem 88 which projects through the end of the main body 81 to be engaged by the lever 72 is arranged to slide in a bushing 89 fitted in a bore 90 of the body portion 81. Between the valve 82 and the end sliding in the bushing 89 the valve stem 88 is reduced in diameter as at 91 to permit free passage of air in the bore 86 and forms a shoulder 92 cooperating with a bore 93 between the central chamber 87 and an exhaust chamber 94. A vent 95 to atmosphere is provided in the wall of the body portion 81 leading from the exhaust chamber 94. The pipe line 58 in this embodiment is adapted to be connected at a threaded aperture 96 with the central chamber 87. With the valve in the position as shown in Figure 7 the pipe line 58 is connected through the central chamber 87 and

the bore 93 with the exhaust chamber 94 and the pressure in the pipe line 58 is reduced to atmosphere through the vent 95. As the valve stem 88 moves to the left to the position shown in Figure 8 the bore 93 is closed by the valve stem 88 at the shoulder 92 cutting off the atmospheric escape from the port 95, and simultaneously the valve 82 is lifted from its seat 84 permitting compressed air to pass from the chamber 85 into the central chamber 87 and thence into the pipe line 58 to actuate the piston 55 whereupon the regulator acts as before described to operate the unloading valves R, S, T, U, V, W, X and Y to unload the compressor.

I claim:

1. In an inter-control system, the combination of two power driven devices and means for decreasing the power consumption of one of said devices while the other said device is being started in operation including a pneumatic unloader for the first said device and a valve associated with the second said device adapted to supply pressure fluid to said unloader during the acceleration period of said second device and adapted to exhaust the pressure fluid from the unloader thereafter to reload the first said device.

2. In an inter-control system, the combination of two power driven devices and pneumatic means for decreasing the power consumption of one of said devices while the other said device is being started in operation including a pneumatic unloader for the first said device, a pilot valve adapted to supply pressure fluid to said unloader and to exhaust the pressure fluid therefrom, and an electro-pneumatic relay for controlling said pilot valve automatically operable during the acceleration period of the second said device.

3. In an inter-control system, the combination of two power driven devices, a starting means for one of said devices, and an automatic pneumatic means associated with said starting device for decreasing the power consumption of one of said devices in anticipation of and only during the acceleration period of the other said device.

In testimony whereof I have signed this specification.

HARRY V. HAIGHT.
